UNITED STATES PATENT OFFICE

1,976,566

OUTLET BOX

John Knell, Aurora, Ill., assignor to All-Steel-Equip Company, Aurora, Ill., a corporation of Illinois

Original application March 14, 1931, Serial No. 522,553. Divided and this application August 31, 1931, Serial No. 560,383

1 Claim. (Cl. 247—26)

This invention relates to electric receptacles and particularly to outlet boxes.

This application is a division of application, Serial No. 522,553, filed March 14, 1931, for outlet box.

The primary object of the present invention is to provide an improved outlet box which has new and novel knock-outs in the walls thereof, which is provided with simple and efficient means for permitting the knock-outs to be removed by a tool, such as a screw-driver, and which has the knock-outs connected to the walls of the box by an integral fin or contact.

A further object is to provide an outlet box having knock-outs in the walls thereof, the knock-outs being provided with slots therein into which a tool, such as a screw-driver may be inserted for twisting or otherwise removing a knock-out from a wall.

20 Numerous other objects and advantages will be apparent throughout the progress of the following specification.

The invention comprises in general an outlet box having knock-outs provided in the walls of the box and which are integrally connected to the walls by one or more fins. Slots or openings are provided in the knock-outs to receive a tool, such as a screw-driver, to permit the knockouts to be quickly and easily twisted or otherwise removed from the walls.

The accompanying drawing illustrates a selected embodiment of the invention and the views therein are as follows:

Fig. 1 is a detail perspective view of the improved outlet box showing the manner in which some of the knock-outs may be pried or otherwise removed from the walls of the box.

Fig. 2 is a detail view showing a knock-out connected to a wall of the box by a single intact portion.

Fig. 3 is a detail plan view of a box showing the knock-out provided with more than one fin.

Fig. 4 is a detail sectional view showing the slot in the knock-out provided with inclined side walls.

The particular box herein shown has a body which may be of any conventional shape and which is made of metal, as usual. The walls of the outlet box are provided with knock-outs 31 each of which has a line of rupture 32 made by embossing or cutting. The knock-outs 31 may be raised and parallel with the body walls of the box, as shown in the various figures, or they may be made normally flush with the walls. If desired, these knock-outs are connected to the walls

of the outlet box by one or more contacts or fins 33 and may have a slot 34 provided in the walls of the knock-outs for the reception of a tool 35 for prying out the knock-outs. These slots may be horizontal, vertical, or diagonal, as shown in Fig. 1.

In Fig. 4 a slot 36 is substituted for the slot 34, this slot 36 being inclined through the knock-out so that the full opening through the top, while being as large as the others, presents only a small perpendicular opening. This would cause any flash or spark to make an angle turn before it could discharge from the box. In other words, the spark or flash would be intercepted and in all probability would never find its way out of the box.

While the slots 34 and 36 are shown elongated, it is to be understood that round or square holes may be substituted for the particular slots herein shown.

The invention provides new and novel means for effectively removing a knock-out from a wall of the box without the necessity of driving the knock-out inside of the box or deforming the knock-out in any way. The impact interrupts the line of rupture and holds the knock-out securely in position.

Changes may be made in the form, construction, and arrangement of the parts without departing from the spirit of the invention or sacrificing any of the advantages thereof, and the right is hereby reserved to make all such changes as fairly fall within the scope of the following claim.

The invention is hereby claimed as follows:

An outlet box comprising a body having walls, a knock-out in a wall of said body, said knock-out being disposed in parallelism relative to said wall, an integral fin connecting the knock-out to the wall, said knock-out having a slot therethrough for receiving a tool for prying off the knock-out, the side walls of the slot being inclined in respect to said wall.

JOHN KNELL.
